UNITED STATES PATENT OFFICE.

FRANZ LÖSEL, OF BRUNN, CZECHOSLOVAKIA.

STATIONARY GUIDE-NOZZLE CONSTRUCTION AND ASSEMBLY FOR TURBINES.

Application filed July 17, 1924, Serial No. 726,458, and in Austria July 26, 1923.

This invention relates to elastic fluid turbines.

The object of the invention is to provide turbine guide nozzle structure and assembly 5 possessing certain novel features of construction which contribute substantially to the economical production and accuracy of construction and without impairing the turbine performance under service conditions. More 10 particularly the invention relates to a new stationary guide nozzle and separating diaphragm structure for disc wheel turbines and a new manner of manufacture and assembly thereof whereby the above indicated 15 improvements are effected, as more fully hereinafter set forth.

For a better understanding of the invention, reference may be had to the accompanying drawings wherein:

20 Fig. 1 is a part sectional view of a turbine embodying the invention;

Fig. 2 is a longitudinal section at right angles to Fig. 1;

25 Fig. 3 is a plan view of a portion of a separating disc with parts of the turbine casing broken away;

Fig. 4 is a section along the line 4—4 of Fig. 2;

30 Fig. 5 is a perspective view of a guide nozzle element;

Fig. 6 is a plan view of an element blank illustrating a step in the manufacture, and

35 Fig. 7 is a perspective view illustrating a further step in the manufacture of an element.

Referring to the drawings, I have illustrated my invention as embodied in a turbine having rotor wheels 1, a surrounding casing or other diaphragm support 2, and separating 40 diaphragms or discs 3 (only one shown in drawings). The rotating canals are indicated at 4 and the stationary guide nozzle canals at 5. The latter are formed in guide

45 nozzle elements 6 of the character illustrated in Fig. 5 and these elements are assembled in abutting relation about the periphery of the diaphragms 3 and guided at their outer ends in annular grooves 7 formed on the interior of the turbine casing or a special carrier body 2. The nozzle elements 6 are formed with identical abutting side curved 50 surfaces 8 and 9, the concave side 9 of each element matching and fitting tightly against the convex side 8 of the next adjacent element. The end surfaces 10 of the elements 55 are plane parallel surfaces at right angles to

the rotor shaft so as to fit easily into the guide grooves 7 formed in the casing. The outer surface 11 of each element is slightly curved to correspond to the curvature of the 60 casing 2 and grooves 7 formed therein. Each stationary canal 5 is cut entirely through a single nozzle element 6, namely through one side thereof, whereby when the elements are assembled in closely abutting relation about the periphery of the diaphragms each element forms the side closing wall of the canal in the next adjacent element. In the particular and preferred embodiment herein shown, the canals 5 are formed in the convex 65 sides of the elements, and the concave sides of the next adjacent elements form the closing walls for the canals. The curvatures of the sides 8 and 9 must therefore be of a character to conform to the concave wall of the 70 nozzle canals. The nozzle elements 6 may be mounted upon the diaphragms 3 in any suitable manner and are here shown as having wedge shaped attaching lugs 12 which are inserted in similar shaped annular 75 peripheral grooves about the diaphragms 3 with attaching pins, rivets or screws 13 passing transversely through to hold them in position. The attaching members 13 may be omitted in certain of the elements, as indicated in Fig. 1, since the unsecured wedge like nozzle elements are firmly held against movement in the peripheral direction between a pair of secured elements and against movement in other directions by the pressure 80 and friction of the other nozzles and by the grooves in the diaphragm and in the casing. In certain cases it is desirable to provide a slight radial play of the guide nozzles within the grooves 7, as indicated.

85 Figs. 6 and 7 indicate steps in the formation of the individual nozzle elements 6 before they are assembled about the diaphragms. Fig. 6 indicates a plan view of an individual guide nozzle blank which is severed on the bias from a ring or profile piece *a* and has parallel opposite walls 8' and 9', and 10' respectively. These blanks are preferably formed from rings of rectangular section of the width of the blades and the diaphragms and of substantially the diameters of the ring of assembled individual guide nozzle elements, the ring being cut on a bias along planes including the ring center to form the sides 8' and 9', although in certain 90 instances it may be desirable to form these blanks from a straight or other shape of bar 105

of desired profile. When the blanks are formed from rings the outer and innermost surfaces thereof are of the desired curvature to fit into the diaphragm and casing grooves, obviating the necessity for special shaping of these. The blank is first manipulated to transform the planar sides 8' and 9' into convex and concave sides 8 and 9 respectively as indicated in dotted lines in Fig. 6. The curvatures of 8 and 9 may, if desired, approximate a cylindrical formation with radii r or any formation to correspond to the desired concave wall of the guide nozzle canals. They are of a radial wedge like shape. Preferably both radial walls 9 and 14 of the nozzle canal are of a cylindrical formation with circles which are tangential to the angles of the entrance- and exit-sides of the blade. In this case the machining work can be easily effected as by turning of the nozzle blank or the milling tool with a minimum of the necessary manipulations. The blank thus formed is indicated in Fig. 7, and the next step is to mill or cut out the canal 5 as indicated in dotted lines. The lower end of the element is formed as indicated in dotted lines with the wedge like foot 12 and the nozzle elements thus obtained are assembled into the structure illustrated and in the manner indicated above.

The full admission stationary guide nozzle structure thus obtained has the advantage that each canal is formed entirely through one side of a nozzle element and intermediate its upper and lower surfaces and with the concave side of the adjacent element forming the closure for the canal there are only two joints through which the steam may leak. There is no cover strip for the ring of guide nozzles, the necessity for such part being obviated in my invention, and the loose assembly of the individual elements contributes to economical production. Moreover, economical production is assured by my novel method of forming the blanks on a bias, and then manipulating them in the manner set forth to obtain accurately fitting concave-convex nozzle elements which may be readily fitted together about the diaphragm peripheries to form rings of abutting elements with accurate and smooth canals formed therein of the exact curvature desired.

I claim:

1. In a multistage disc wheel turbine a casing element having an annular guide groove formed on the interior thereof, and a diaphragm and nozzle unit disposed in the plane of the groove and separating two adjacent rotating wheel elements, comprising an inner disc member and an outer ring of individual abutting nozzle elements forming the stationary guide means and carried on the disc periphery and pins adapted to secure said nozzle elements to the diaphragm,

said nozzle ring having its outer peripheral edge disposed in and guided by the groove in the casing element and the unit including the nozzle elements being radially relatively separable from the casing element and said guide nozzle elements being radially relatively separable from the diaphragm member. 70

2. In a multistage disc wheel turbine a casing element having an annular guide groove formed on the interior thereof, and a diaphragm and guide nozzle unit disposed in the plane of the groove and separating two adjacent rotating wheel elements, comprising an inner disc section and a ring section of abutting guide nozzle elements carried on the disc periphery and guided at their outer edges by the groove in the casing element, each of said guide nozzle elements having a full canal formed therein on one side intermediate its outer and inner surfaces and having radial abutting surfaces of a curvature corresponding to the side wall of the canal so as to form a closing wall for the adjacent guide nozzle canals, and said casing element being radially removable from the diaphragm and guide nozzle carrier unit and said guide nozzle elements being radially relatively separable from the diaphragm member. 75 80 85 90

3. In a multistage steam turbine of the type having a multiplicity of disc wheels and separating diaphragms, including a casing element having a plurality of annular guide grooves formed on the interior thereof and alternating with the wheels and a plurality of diaphragm and guide nozzle units disposed in the planes of said grooves and separating the rotating wheel elements, each of said units comprising an inner disc section and a ring section of abutting guide nozzle elements carried on the periphery thereof and guided at their outer edges by the groove in the casing element, each of said guide nozzle elements having a canal of full dimensions formed in one of its abutting surfaces intermediate its upper and lower surfaces and having radial abutting surfaces of a curvature corresponding to the canal curvature, and each of said diaphragm and stationary nozzle units being relatively radially removable from the guide groove of the casing element and said guide nozzle elements being radially relatively separable from the diaphragm member. 95 100 105 110 115

4. In a multistage disc wheel turbine a casing element having an annular guide groove formed on the interior thereof, and a diaphragm and nozzle unit disposed in the plane of the groove and separating two adjacent rotating wheel elements, comprising an inner disc member and an outer ring of individual abutting nozzle elements forming the stationary guide means and carried on the disc periphery, said nozzle ring having its outer peripheral edge disposed in and 120 125 130

guided by the groove in the casing element and the unit including the nozzle elements being radially relatively separable from the casing element and said nozzle ring having 5 a substantial play within the annular guide groove in the casing.

5. In a multi-stage disc wheel turbine a casing element having an annular guide groove formed on the interior thereof and a 10 diaphragm and guide nozzle unit disposed in the plane of the groove and separating two adjacent rotating wheel elements comprising an inner disc section having an an-

nular wedge-shaped peripheral groove thereon and a ring section of individual abutting 15 guide nozzle elements having corresponding wedge-shaped feet disposed in the wedge-shaped groove and guided at their outer edges by the groove in the casing element, whereby the nozzle elements are relatively 20 radially separable from both the annular guide groove in the casing and from the carrying groove of the disc.

In testimony whereof, I have signed my name to this specification.

FRANZ LÖSEL.
